MEANS FOR FORMING CLINCH NUTS

Charles T. Langmaid and Plummer E. Double,
Detroit, Mich.

Application June 13, 1939, Serial No. 278,935

5 Claims. (Cl. 10—76)

This invention relates to clinch nuts and has particular reference to the means for forming clinch nuts, similar to the type disclosed in Patent No. 2,110,039 issued March 1, 1938.

5 The nut proposed to be made through the practice of the present invention, however, is formed with the corners of the body portion rounded instead of square.

10 The practice of forming slight radii on the body portion has certain definite advantages in commercial practice. It has been found that clinch nuts having bodies with absolutely square corners oftentimes cause the metal of the securing piece to crack at the corners when much stress is placed on the nut so secured, whereas 15 the nut having the rounded corners will distribute the stress and strain more evenly to the securing piece. It has also been found that a nut having the body formed with a slight radius at 20 each corner is much easier located in the corresponding aperture of the securing piece.

25 The within invention contemplates the production of such improved nuts by the means herein disclosed whereby great economies in time and necessary equipment are effected.

30 Nuts having the body portion formed with rounded corners have heretofore been formed by "cold heading" methods, which are slow and comparatively expensive, in that they usually 35 require special cold heading machines and dies with two or three or more stations, whereas this invention calls for a device which forms the round corners and punches the hole in the nut at a single station, the forming die being utilized to hold the nut blank while it is being punched.

35 This improved device may be used on an ordinary press and may be operated off the press header so that the forming and piercing may 40 be accomplished in a single timed operation. With this device it is possible to form and pierce nuts at the rate of 200 strokes a minute, which is double the present known production rate.

45 The invention has a further advantage, in that it permits a clinch nut to be formed with the corners of the body rounded, without distorting the nut, and without the necessity of working on the flange of the nut as well as the body portion, as is done in the cold heading process. It 50 is well known that the more the metal of the nut is worked, the harder it becomes, therefore, the harder it is to tap.

The means herein disclosed enables the manufacturer to produce a clinch nut which has 55 some of the metal at the corners displaced up-

wardly. This results in a comparatively increased thickness of metal at the corners, which, when again displaced outwardly over the securing member during the attaching operation, makes a much firmer connection.

5 The foregoing objects and advantages of the invention, and others, will be better understood as the description proceeds, reference being made to the accompanying drawings, which form a part of the disclosure, wherein:

10 Fig. 1 is a plan view of the forming and punching dies embodying our invention.

15 Fig. 2 is a vertical section taken substantially on the line 2—2 of Fig. 1.

20 Fig. 3 is a view similar to Fig. 1, but showing the dies in the closed position or position of work.

25 Fig. 4 is an enlarged fragmentary detail in section taken substantially on the line 4—4 of Fig. 3, and illustrating the manner in which the cams function to actuate the dies.

30 Fig. 5 is a fragmentary detail, taken substantially on the line 5—5 of Fig. 3 and illustrates the manner in which the nut is held in position by the forming die during the piercing operation.

35 Fig. 6 is an enlarged fragmentary detail taken substantially on the line 6—6 of Fig. 3, further illustrating the piercing operation immediately following the forming operation. This view further illustrates a portion of the tucker mechanism, showing how the nut is maintained in the slot under spring tension.

40 Fig. 7 is an enlarged fragmentary view, partly in section taken substantially on the line 7—7 of Fig. 3, illustrating the feeding mechanism for supplying the nut blanks to the forming and piercing dies.

45 Fig. 8 is an enlarged fragmentary detail partly in section, illustrating a nut blank in position, ready to be worked on in the forming operation.

50 Fig. 9 is a view similar to Fig. 8 but showing the nut blank after the body portion has been formed with a radius at each corner and being held for the subsequent piercing operation. This view illustrates how the metal at the corners is displaced upwardly during the forming operation.

55 Fig. 10 is an enlarged fragmentary perspective view of one element of the forming and holding die. This view illustrates the die cavity with a vertical passageway for the entrance of the punch and the horizontal passageway for the entrance of the stripper pin.

Fig. 11 is a perspective view of a length of preformed steel, from which the nut blanks are cut.

Fig. 12 is a perspective view of a nut blank 5 before it is formed and pierced. This view illustrates how the body of the nut may be formed with a radius at each corner without in any wise distorting or affecting the flange portion of the nut.

10 Fig. 13 is the nut blank illustrated in Fig. 12 after it has been formed and pierced.

Fig. 14 is an enlarged fragmentary detail partly in section diagrammatically illustrating the tapping of the formed and pierced blank illustrated in Fig. 13.

15 Fig. 15 is a perspective view of the nut after it has been formed, pierced and tapped and ready to be secured to another element.

Fig. 16 is an enlarged fragmentary detail in 20 section illustrating the manner in which the nut illustrated in Fig. 15 is secured to another element, such as a sheet of metal.

Fig. 17 is a perspective view of the nut illustrated in Fig. 15, after it has been attached to 25 an apertured sheet of metal.

Referring now more particularly to the drawings, it will be seen that the means for practicing our invention comprise the forming and holding dies 20 and their associated elements, 30 as hereinafter described. The disclosure shows a compound die capable of handling two nuts at a time. The forming and holding dies 20 are made in two sections 20a and 20b which are adapted to reciprocate in suitable slots 21, 35 formed in the bed plate 22, the latter being adapted to be secured in any suitable manner to a conventional punch press. The die sections 20a and 20b are secured in the slots 21 by suitable plates 23, which plates are adapted to over-ride off sets formed along the sides of the die sections 20a and 20b. The plates 23 are secured to the bed plate 22 by means of suitable machine screws 24. Angular heel plates 25 are secured to the bed plate 22 by means of machine screws 26. The heel plates 25 are adapted to limit the return movement of the die sections 20a and 20b, and in addition thereto serve as supports and guides for the return bolts 27, which extend through apertures formed therein. The bolts 27 are threadedly secured as at 40 28 to the die sections 20a and 20b. Springs 29 are positioned between the heel plates 25 and the heads of the bolts 27, and are intended to hold the die sections 20a and 20b in the position of rest, shown in Figs. 1 and 2. The working faces of the die sections 20a and 20b are provided with two or more matched recesses 30, as illustrated in Fig. 10, wherein it will be seen that the recesses are formed with a slight radius 31 at each corner. Each recess 30 has 45 a vertical passageway 32, extending into it, which passageway is intended to permit the entrance of the punch as hereinafter explained. Each of the die sections has a horizontal passageway 33, Fig. 10 communicating with at least 50 one of the recesses 30, which passageway 33 is intended to accommodate a stripper pin 34, which is secured by any suitable means in the bed plate 22. The stripper pins 34 are intended to strip the nuts from the recesses 30 as hereinafter explained. Rectangular apertures 35 are formed in the bed plate 22 and communicate with chutes 36, Fig. 2, which are adapted to carry away the nuts after they have been formed and pierced as hereinafter explained.

75 It will be noted that there is but one strip-

per pin for each die section. One pin for each section is all that is required for the reason that after the nuts have been formed and pierced as hereinafter explained, the nuts will be stripped from opposite sections of the dies by the edges 5 of the feed slots 37, which are machined in the bed plate 22 and in which the nuts are held during the forming and piercing operations. The edges of the feed slots 37 adjacent the apertures 35 are machined away to enable the nuts 10 to be pulled out of the feed slots 37 and carried over the apertures 35 by the movement of the respective adjacent die sections. As the nuts reach positions above the apertures 35, they are stripped from the recesses by the pins 34 15 and dropped into the chutes 36.

Apertures 38 are formed in the bed plate 22 to accommodate the punches and to permit the slugs, which are punched from the nut blanks, to be carried away.

20 Nut blanks are fed to the dies by means of tracks 39, which tracks communicate with conventional selection hoppers (not shown). A tucker track 40 is secured to the bed plate 22 (Fig. 6) as at 41 and is adapted to communicate with 25 the feed slots 37 machined in the upper surface of the bed plate 22 and is adapted to carry nut blanks 42 from the feed tracks 39 to the feed slots 37. A tucker 43 is adapted to ride in the tucker track 40 and move the nut blanks 30 42 into the feed slots 37. The tucker 43 is provided with a slot, in which is slidably mounted a pin support 44, to which is secured a pin 45, which is in turn adapted to engage a slot formed in the rocker arm 46, which is pivoted as at 35 47 to a suitable bracket secured to the bed plate 22. A compression spring 48 is positioned between the pin support 44 and the tucker 43 to give a resilient action. The rocker arm 46 is adapted to be actuated by the cam 49, which is secured by any suitable means to the punch 40 press header 50. The return of the rocker arm 46 to its position of rest, as shown in Fig. 1, is accomplished by means of the spring 51. A set screw 52 is provided to serve as an adjustable stop for the rocker arm 46. The cam 49 45 is timed to actuate the rocker arm 46 and the tucker 43, so that a nut may be moved into position to be worked on before the die sections 20a and 20b become together.

The die sections 20a and 20b are actuated 50 by the large cams 53, which are also secured by means of suitable machine screws 54 to the press header 50, as illustrated in Fig. 2. The press header 50 also carries the punches 55. The large cams 53 are bifurcated to permit the bolts 55 27 to operate there-through. The cams 53 are provided with angular cam surfaces 56, which are adapted to engage correspondingly angular faces 57, which are formed on the die sections 20a and 20b. The bed plate 22 is provided with 60 apertures 58 to permit the cams 53 to extend there-through. The cams 53 are timed so that they will actuate the die sections 20a and 20b after a nut has been placed in position in the feeder slot 37. The punches 55 are timed to 65 pierce the nut blanks 42 immediately after the forming operation and while the die sections 20a and 20b are held in the closed position as illustrated in Fig. 3.

70 It will thus be seen that the operations of feeding the nut blanks to the dies forming the radii on the bodies of the nuts and piercing the holes through the nuts are all accomplished in one downward movement, of the press header 50. This enables us to accomplish several op- 75

erations with one stroke of the press, thus obviating the necessity of having progressive dies with two or more operating stations, thereby greatly increasing the production rate.

5 After the nuts are formed and pierced, they are then tapped as indicated in Fig. 14 and are ready for attachment to other elements, such as a sheet of metal 59 as suggested in Figs. 16 and 17.

10 The operation of the device is obvious from the foregoing description. The nut blanks are fed into the feed slots 37 by means of the tuckers 43. Their forward movement is arrested by the ends of the slots 37. Their backward movement is prevented by resilient pressure exerted on them by the tuckers 43. While the nuts are being held in the position just described, the continued downward movement of the press header 50 causes the large cams 53 to actuate the die sections 20a and 20b, causing them to approach one another. Upon the completion of the inward movement of the die sections, the bodies of the nuts held in this position are worked upon forming the radii at the corners.

15 After the forming operation and while the die sections are held in closed position and upon the same stroke of the press header 50, the punches 55 enter the openings 32 in the die sections, thereby piercing the holes in the blanks.

20 From the foregoing it will be seen that with this device it is possible to form the radii on the bodies of the nuts without in any way disturbing the corners of the flanges of the nuts as is the case in most cold heading processes.

25 Upon the upward movement of the press header 50 the die sections 20a and 20b, under the influence of the springs 29, start their movement away from each other. The flanges of the nuts remain in the slots 37 while the bodies of the nuts are firmly held in the recesses 30 of the die sections.

30 The nuts are prevented from traveling in one direction with the die sections by the walls of the slots 37. The walls of the slots 37, adjacent the rectangular apertures 35, are machined away, however, so that the nuts may follow the die sections in the opposite direction and be removed from the slots 37. The nuts follow the receding die sections so holding them until they are immediately above the apertures 35, whereupon they are struck by the stripper pins 34. The nuts are then entirely free of the die sections and fall of their own weight through the apertures 35 into the chutes 36, from whence they are removed to the tapping machines.

35 Having described our invention what we claim and desire to secure by Letters Patent is:

1. A device for forming round cornered, flanged clinch-nuts, comprising a base plate, blank feeding means, a groove in said base plate adapted to engage the flanges of blanks received from said feeding means, dies for forming radii at the corners of the bodies of said blanks, means to actuate said dies and means to pierce said blanks while they are held in said forming dies. 5

2. A device for forming clinch-nuts from blanks having a T-shaped cross section, comprising a base plate adapted to be secured to a punch press, blank feeding means, a groove in said base plate adapted to engage one leg of the T-shaped blanks received from said feeding means, dies for forming radii at the corners of the other leg of 15 said T-shaped blanks, cams carried by the punch press header for actuating said feeding means and said dies, and punches carried by said press header, adapted to pierce a hole in said blanks while the latter are held in said forming dies. 20

3. The combination with a punch press of a device for forming clinch-nuts, comprising a base plate adapted to be secured to said punch press, means on said base plate for receiving nut blanks, each comprising a body portion and a flanged 25 portion, dies carried by said base plate adapted to perform work on the body portions of said blanks, means carried by the header of said press for actuating said dies, a punch carried by said header for piercing holes in said blanks, while the 30 latter are held in said dies, discharge means in said base plate, and stripping means carried by said base plate adapted to remove the nut blanks from said dies and deposit them in said discharge means. 35

4. The combination as defined in claim 3, including means for feeding nut blanks to said base plate and means actuated by said press header for motivating said feeding means.

5. The combination with a punch press of 40 means for making clinch-nuts, comprising a base plate, means on said base plate for receiving nut blanks, slideable dies carried by said base plate adapted to form radii on said nut blanks, heel plates secured to said base plate, resilient means 45 supported by said heel plates for holding said dies in a position of rest, cam means carried by the press header for moving said dies into the position of work, punches adapted to pierce said nut blanks while said dies are in the working position, and means carried by said base plate for removing the nuts from said base plate and said dies. 50
